3 Claims. (Cl. 346—108)

1

This invention relates to a method and apparatus for automatically measuring and plotting a series of images of varying sizes such as a series of images of the pupils of the eye.

The invention is particularly useful in the diagnostic procedures of pupillography. The method of pupillography has been described in many former publications of the present inventor, for example, Archives for Psychiatry 1927, pages 285-297 (German), The Physiology and Pathology of Pupillary Movements, Particularly in Schizophrenia (Berlin 1933); The Light Reflex of the Pupils in Syphilitic Lesions of the Central Nervous System (Basel, Switzerland, 1935); The Psychosensory Restitution Phenomenon (Basel, Switzerland 1937, German); Les Troubles du Réflexe Pupillaire a la Lumière Dans Les Affections Syphilitiques du Système Nerveux Central (Paris 1939, French); Present State of Pupillography; Its Method and Diagnostic Significance. (With E. D. Friedman, Archives of Ophthalmology, volume 27.)

In short the method of pupillography comprises the steps of (1) taking a series of photographs of the pupils of the eyes under the influence of different stimuli, (2) thereafter measuring, plotting and/or drawing a curve of the pupil diameters of the eyes as they were affected by the stimuli and (3) then comparing the resultant curve or graph with the curve or graph of the normal reaction or with the curve or graph of certain known abnormal reactions.

In taking the series of photographs the apparatus must be devised to provide for sharp clear photographs of each eye. Each of the eyes must be focused separately by separate optical systems since some patients hold their head at a slight angle and since some patients have one eye which is more deeply set in the orbit than the other. Since the horizontal eye spacing is different for different individuals it is also necessary to make the space between the optical systems adjustable. Two conflicting factors make the photographing difficult: On the one hand, the two optical systems must be brought close together so as to obtain the images of the two eyes close to each other. On the other hand, the photographing must be done rapidly with infra red light and infra red sensitive film so that lenses of large diameter (or in other words lenses with a small focal ratio or f-number) are very essential to obtain the required exposure of the film.

Heretofore, in the plotting of the curves, it has been necessary to manually measure the

2

diameter of each pupil in each of the pictures taken. In the measuring of the eyes an accuracy of about 99.25% is necessary to make a satisfactory diagnosis.

5 It is an object of this invention to provide a method and apparatus for automatically and accurately producing a plot of the series of pupil diameters.

10 Another object of this invention is to provide a method and apparatus for measuring and plotting the various diameters of the pupils recorded on a series of photographs.

15 Another object of the invention is to provide a method and apparatus for automatically measuring and photographically plotting the diameters of a series of pupil images.

20 Another object of the invention is to provide a method and apparatus for automatically measuring and photographically recording the plots of the diameters of the pupils in a series of images of the two eyes in such a way that the recorded plots of the variations in diameters of the two eyes are superposed and can be distinguished from each other.

25 These objects and others ancillary thereto are obtained by taking the series of pictures of the eyes by means of a camera which has two closely spaced photographic objectives which are separately adjustable toward and away from the eyes for focusing and are also adjustable laterally with respect to each other. In order to employ large lenses (with a small f-number) as objectives the adjacent edges of the two lens objectives may be cut away or the lenses may be placed at a slight angle to each other. In the second step the diameters of the images of the eyes obtained by the first step are obtained by a process and apparatus which causes a photoelectric cell to scan the images of the pupils and provides a 30 means for measuring and recording the diameters of the pupils as measured by the photoelectric cell and scanning means. The scanning is obtained by employing a projector to project the images of the eye toward a slit behind which 35 a photoelectric cell is situated. Motion of the slit transversely with respect to the images may be obtained, by moving the slit while holding the image stationary, by moving the image across a stationary slit or by moving both image and 40 slit.

45 The E. M. F. delivered by the photoelectric cell in response to the light received from the image, after preamplification, is fed onto the "direct input" terminal of an R. C. A. No. 327A oscilloscope, equipped with single sweep circuits. The 50

sudden application of voltage, as the image of the pupil enters the slit, causes the single sweep to be triggered. The trace is thus started in a deflected position and remains deflected until the opposite pupillary border is reached, when the voltage disappears and the trace consequently drops down, so that the sweep is completed in its zero position. A photograph of a small part of the downward moving portion of the trace on the oscilloscope represents the diameter of each pupil and the photographs of the series of downward traces may be taken on specially prepared film or paper so that the changing diameter of the pupil can be read directly from this photograph.

In preparing the first set of photographs from the eyes of the patient infra-red light and infra-red sensitive film is preferably employed. The human eye is least sensitive to this type of light and where additional light is to be employed as the stimulus, a green light to which the human eye is most sensitive and to which the infra-red film is least sensitive is effective. Large lens objectives are employed for the camera and these should be made separately adjustable in at least two directions, i. e., toward and away from the eye and laterally. The adjacent edges of the lenses can be ground off to permit the lenses to be moved close together to obtain a photograph with the images of the two eyes close together.

In the measuring of the pupil diameter the unsettling influence of the light passed by the iris of the eye interferes with the proper measurement of the pupil, because it constitutes a variable value. In patients with blue eyes which reflect less infra-red light than brown eyes, the iris will appear lighter on the film. This reduces the contrast between the iris and pupil portions of the picture. In case of a very light iris, its value may be so high that the single sweep is actually triggered by the iris, and when, in an effort to prevent this, the synchronous gain of the oscilloscope is reduced, the value of the pupil will also fail to trip the sweep. In order to overcome this effect means for applying a counter voltage to the output of the photoelectric cell and a rectifier-trigger circuit is provided so that the trigger point of the photoelectric cell can be adjusted for each individual set of photographs.

To obtain a permanent plot of the variation in diameters of the pupils, a camera is arranged to take a picture of small portion of the downward path of the trace of the oscilloscope. Suitable means are provided to differentiate the alternate images so that the plot of right and left eyes can be distinguished.

The novel features characteristic of this invention are set forth with particularity in the appended claims. The invention itself, however, both as to its organization and its method of operation, together with additional objects and advantages thereof, will best be understood from the following description of specific embodiments when read in connection with the accompanying drawings in which:

Figure 1 is a perspective view illustrating how the pictures of the eyes are taken.

Figure 2 is a diagrammatic showing of the optical system of the camera.

Figure 2A is a perspective view of the mounting means for the objective lenses of the camera.

Figure 2B is a diagrammatic view of the two lenses in a camera showing how the large lenses (with small f-numbers) having the adjacent sides

cut away can be employed to take the pictures of the eyes.

Figure 2C is a diagrammatic view of a modified optical system employing large lenses which however are placed at an angle to the horizontal.

Figure 3 is a view of the film containing a series of images of the eyes.

Figure 4 is a diagrammatic plan view of the apparatus for measuring the sizes of the pupils.

Figure 4A is a detail view of the rotating mirror of Figure 4.

Figure 5 is a view of the screen of the cathode ray tube.

Figure 6A and 6B are views illustrating the response of the apparatus to the iris and pupil of the eye.

Figure 7 is a detail view showing the camera taking a picture of a portion of the screen of the cathode ray tube.

Figure 8 is a view of the plot obtained by the camera of Figure 7.

Figure 9 is a perspective view of a modified form of apparatus.

Figure 10 is a plan view of an apparatus similar to that of Figure 9.

Figure 11 is a plan view illustrating another modified form of the apparatus.

Figure 12 is a detail view of the camera of Figure 4.

Figure 1 illustrates how the pictures are taken. The eyes 10 and 10' of the patient are illuminated by rays projected from light source 11 and 11' containing the infrared filters 111 and 111'. The pictures of the separate eyes 10 and 10' of the patient are taken by a camera 12 having two objectives 13 and 14. A stimulus is applied to one or both of the eyes of the patient by light source 15 and 16 which may contain green filters 15' and 16'. Usually only one eye at a time is stimulated by green light, for example, and the response of the pupils of the two eyes are compared.

In order to bring the photographs of the eyes close together the optical system shown diagrammatically in Figure 2 is employed. The camera objective contains lenses 17 and 18. The eye 10 is imaged by lens 17 at 19 and the eye 10' is imaged by lens 17 at 21. Similarly the eye 10' is imaged at 20 and the eye 10 at 22 by the lens 18. Only the two inside images 19 and 20 are photographed by the film 25. A shield 103 extending from between the lenses 17 and 18 down to the film 25 is provided to prevent any interference due to overlapping of the two images, etc. As shown in Figure 1, the mounting means for the objectives is provided with a fine adjusting means 13' for one objective which is adapted to move the objective 13 towards and away from the subject independently of the other objective 14 so that differences in the inset positions of the eyes of the patient, etc., can be compensated for. The objective 14 contains an adjusting knob 14' which is adapted to move the objective 14 laterally with respect to the objective 13 so that patients having different pupillary distances may be photographed.

It is also necessary to adjust the apparatus to compensate for patients who tilt their heads. One method to compensate for this tilt is by tilting the camera. Another method of compensating may be employed as shown in the modified device of Figure 2A. In the device of this figure not only is the objective 113 adjustable in and out by the focusing device 113' and the objective 114 is adjustable laterally with respect to the objective 113 but the whole ob-

jective system is rotatable so as to permit the objectives to be tilted to compensate for the tilting of the head of the patient. It is important for the patient to be at ease during the photographing process and if it is natural (or more comfortable) for a patient to tilt the head he must be allowed to do so.

Figure 2B is a detail view of the lenses of the two objectives shown in Figure 1 and illustrates how the lenses 17' and 18' are ground away at the adjacent edges 117 and 118 respectively so as to permit employment of large lenses and yet obtain close spacing of the optical centers of the lenses.

An improved type of lens system and the optical path of the light rays is shown in Figure 2C. In the device of this figure the lenses 17'' and 18'' are tilted at a slight angle to the horizontal so that the images formed by said lenses will be closer to each other and more space is thus provided between the lenses 17'' and 18''.

The camera 12 is a motion picture type of camera and takes a series of negative images such as shown in Figure 3. This is the film from which it is necessary to obtain and plot the changing size of the diameters of the pupils. Heretofore the best method of measuring these diameters has been to project the picture on a screen to obtain a sharp, clear, large image and then measure and plot the change in size of each pupil individually by hand.

Figure 4 shows diagrammatically one method and means for automatically measuring and plotting the sizes of the pupils according to the present invention. In this figure, the projector 30 projects the images of both eyes in rapid succession toward the stationary mirrors 31 and 32. A screen or shield 33 is placed between projector 30 and mirrors 31 and 32 so that the images of one eye only are projected onto mirror 31 and the images of the other eye only are projected onto mirror 32. Mirrors 31 and 32 are adjustably mounted so that they can be tilted or pivoted as shown in Figure 9. The images from mirrors 31 and 32 are directed toward a rotating mirror. As the mirror 34 rotates it reflects first an image from mirror 31 and then an image from mirror 32, etc. The reflected images from rotating mirror 34 pass across a slit 35, and fall upon the photoelectric cell 37. The output of the photoelectric cell after being twice amplified and rectified is fed to the oscilloscope. The rectifier is interposed between the second stage amplifier and the oscilloscope. A countervoltage is applied at 56' to the once amplified voltage of the photoelectric cell to bring the desired measuring point (immediately above the value of the iris) to ground potential. The rectifier cuts off voltages below ground potential and thereby eliminates the values of the iris.

The sudden shock necessary to trip the single sweep of the oscilloscope is therefore not produced directly by the difference in density of the iris-and-pupil-portions of the image on the film, but is instituted when the rectifier starts conducting as soon as the voltage rises above ground; in other words, the rectifier acts as a trigger. This method is independent of the abruptness or contrast of the change in optical density.

Figures 6A and 6B illustrate how the iris and pupil of one eye may differ in photoelectric response from that of another eye. In these figures the portions of the projected film images which are passed by the screen 33 are shown at 50, 51. In these images 52 and 53 represent a portion of

the iris and 54 and 55 represent the pupils. Just below the images 50 and 51 in Figures 6A and 6B are illustrative traces produced on the oscilloscope when the respective images 50 and 51 are scanned by the photoelectric cell. The line 56 of Figure 6A shows the portion of the trace which must be cut off to produce an accurate curve of the pupil and line 57 shows that a much larger countervoltage must be applied to cut off the iris response of the eye image of Figure 6B than that of 6A. The countervoltage applied by means 56' must therefore be adjusted for the photographs of the eyes of each patient. The two eyes of the same patient may also photograph differently or produce a different response as is illustrated by Figures 6A and 6B although generally the difference in response will be much less for two eyes of the same patient than for the eyes of different patients. However, it is also necessary to adjust the countervoltage for each eye of the same patient. Since this difference is less it has been found advantageous to adjust for the difference between two eyes of the same patient by adding a second countervoltage 57' to the twice amplified voltage as shown in Figure 4. The countervoltage 56' is applied to all responses of the photoelectric cell whereas the countervoltage 57'' is applied to the responses of only the right or the left eye images. The time of applying the second countervoltage 57' is determined by the switch 84.

It is not necessary to see the height of the curve traced by the spot in the cathode ray tube since the downward movement of the spot measures the time required for the image of the pupil to be scanned by the photoelectric cell. It is essential to obtain a substantially square response curve, however, and this type of curve is obtained if the photographs of the pupils are sharp and clear, if the projector is properly focused, and if the proper counter voltages are applied, etc. A typical curve on the screen 59 of the cathode ray tube of a single sweep oscilloscope is shown in Figure 5. Since the speed of the single sweep is uniform, the time taken by the slit to cross the pupil is in direct proportion to the position of the descending branch of the trace on the face of the oscilloscope tube. By proper calibration, the descent is caused to occur at its proper point in reference to a coordinate system 58 covering the range of pupillary diameters.

The trace thus produced on the oscilloscope screen is recorded by means of a moving picture camera which is geared to the movements of the projector and the mirror. The camera aperture covers a narrow slit 61 across the middle of the oscilloscope tube.

The coordinate system is shown in the final photograph (Figure 8) as white lines on a grey background by faintly illuminating the face of the oscilloscope tube with a G. E. 6 watt fluorescent tube emitting light in the violet-ultraviolet range of the spectrum, and by painting the coordinate system black. It may also be caused to appear as dark lines on grey background by painting the lines with fluorescent paint onto the oscilloscope tube. The paint will fluoresce when struck by the violet light, thus appearing dark on the record (Figure 9). The final trace (Figure 8) is thus produced on a sensitized band of film or paper, moving perpendicular to the slit-aperture of the recording camera, advancing intermittently and in step with the projector 30. It consists of a row of black lines, each representing one pupillary diameter, caused by the

descending branch of the single sweep trace as it crosses the center of the oscilloscope tube covered by the aperture of recording camera 60. Two lines are recorded on film 6b (Figure 8) one for the right and one for the left pupil, each time the projector 30 and recording camera 60 are at a standstill.

To differentiate between the traces representing the right and left pupillary diameter, a semi-transparent shutter partly obscures the aperture of the recording camera while one pupil is measured and is open while the other pupil is measured. Because the picture to be covered by this shutter is long and thin, the shutter must also be long and thin. This can be accomplished in various ways, one of which is illustrated in Figure 12.

A separate compartment 160 is located at the side of the camera 60 and contains the film moving mechanism, etc. The drive shaft 161 is connected to or is part of the main drive 161 for the whole apparatus which is driven by the motor 162. The shaft 161 extends through the side 163 into the camera 60 and contains an eccentrically mounted rod 169 which forwards the film intermittently. Connected to the shaft 161 is a gear 164 which meshes with gear 165 which in turn is attached to shaft 166. The shaft 166 is also another gear 170 which meshes with large gear 171 which drives the film transport roller 172. Also attached to the shaft 166 is a cam 173. The shaft 166 is driven to make one complete revolution when each pair of eye images is scanned. A lever 174 is pivoted to the bearing element 168 at 175 and is adapted to be moved by the cam 173. Attached to the free end of the lever 174 is a rod 176 which in turn is attached at the other end to a shutter moving means 180. The shutter moving rod 180 is pivotally attached to the side 163 at 181. Attached to the part of the rod 180 that extends in front of the opening 182 of the camera 60 is the semi-transparent shutter means 183. A spring 184 is attached to the rod 180 and tends to hold the lever 174 against the cam surface of the cam 173. It will be seen therefore that the cam 173 holds the semi-transparent shutter 183 away from the slot 182 for about $\frac{1}{2}$ of each cycle so that the images of the trace which represents the diameter of either the right or the left eye as recorded on the film of camera 60 are always darker than the images which represent the other eye.

Resetting the single sweep is done by a cam and microswitch which is synchronized with the remainder of the apparatus in any suitable way. Figure 4A shows one such arrangement in which two cams are attached to the shaft 70 which rotates mirror 34. The mirror 34 has two mirror surfaces so that four eyes or two frames of the right and left eyes are scanned with each complete rotation of the mirror. The single sweep must be returned to its zero position by the resetting circuit (to ground potential) four times with each revolution of the mirror 34. The resetting cam 71 of Figure 4A therefore has four projections 72, 73, 74 and 75 cooperating with microswitch 76 to reset the oscilloscope. Above the cam 71 is shown the cam 77. This cam has two projecting quadrants 80 and 81 and two indented quadrants 82 and 83. Cam 77 cooperates with microswitch 84 to apply the countervoltage 57' to the voltage developed by the images of one of the eyes.

Figures 9 and 10 show a modified form of the

apparatus which has some advantages over the device of Figures 4 and 9. In the apparatus of these figures the scanning is obtained by a rotating cylinder 85 instead of the rotating mirror 34, of Figures 4 and 4A. The rotating cylinder 85 contains a plurality (4 shown in Figure 10) of slits 86, 87, 88 and 89. These slots or slits are shielded from one side as shown at 90 and 91 in Figure 10. The shields from any two adjacent slits project in opposite directions so that the shield effectively cuts off the light coming from one of the stationary mirrors 31, 32. The cylinder or drum 85 is rotatable on a shaft 92 so that images from the mirrors 31 and 32 are scanned alternately by the slits (Figure 10). Adjacent the outside edges of the slits 86-89 a pair of sharply honed blades 190, 191 are adjustably mounted as by means 192, 193. A suitable lens system 93 directs the light rays passing the slits toward the photoelectric cell 37. Adapted to rotate with the drum 85 are two cams 71' and 77'. The cam 71' corresponds to cam 71 of Figure 4A and acts with the switch 76' to reset the single sweep oscilloscope. The cam 77' corresponds to cam 77 of Figure 4A and cooperates with switch 84' to connect or disconnect the counter E. M. F. which is to be applied at the second stage of amplification similar to the counter voltage means 57' of Figure 4.

Figure 11 shows diagrammatically, another modified form of the invention in which the mirrors are eliminated. The drum 85' contains a number of slits 94, 95. The projector 30' is adapted to project the images of the two eyes from two separate lens systems 96, 97. The light from each image is focused by a lens system 98 or 99 is passed through a stationary shield 100 and is directed toward the photoelectric cell 37 by prism 101 or 102. Cams similar to cams 71, 77 or 71', 77' are attached to the shaft 92' to effect the resetting of the oscilloscope and control the proper counter voltage.

We claim:

1. The method of measuring automatically and registering graphically, a series of consecutive pictures or images of the pupils of the eyes on a transparent film such as obtained by the method known as pupillography comprising the steps of projecting the images intermittently and sequentially in the general direction of a slit behind which is a photoelectric cell, causing the image to be scanned by said slit at a uniform speed by moving the slit and image relative to each other whereby the light establishes a voltage in the photoelectric cell which depends upon the density of the image on said transparent film, amplifying the voltage from the photoelectric cell, feeding the amplified voltage through a counter voltage device which is adjustable to eliminate undesirable low voltage reactions of the photoelectric cell, rectifying the resultant voltage and feeding the rectified voltage to the direct input terminal of a single sweep oscilloscope, resetting the oscilloscope after each image has been scanned, whereby each scanned image of the transparent film traces a square wave on the screen of said oscilloscope, the downward portion of said wave being proportional to the time required for the pupil image to be scanned by said slit, photographing a part of each of the downward portions of said waves on an intermittently moved film of a photographic camera to obtain a plot in which the position of the various photographed parts of the wave on the photograph is proportional to the diameter of the pupil scanned.

2. An apparatus for measuring automatically and registering graphically, a series of consecutive pictures or images of the pupils of the eyes on a transparent film such as obtained by the method known as pupillography comprising means for projecting the images intermittently and sequentially, a slit for scanning the images formed by the projecting means, a photoelectric cell behind said slit adapted to receive the light which passes through said slit, means adapted to move the image from the projecting means relative to said slit, means for amplifying the voltage developed by the light from said slit which falls on said photoelectric cell, means for applying a predetermined counter voltage to the amplified voltage, a single sweep oscilloscope adapted to be triggered by a small positive voltage, a rectifier for rectifying the voltage resulting from the combination of the amplified voltage and the counter-voltage the output of which is connected to the direct input terminal of said oscilloscope, means for resetting the oscilloscope after each image has been scanned, means for photographing a corresponding portion of each response curve which is traced on said oscilloscope.

3. An apparatus for measuring automatically and registering graphically a series of consecutive pairs of pictures or images of the right and left pupils of the eyes such as obtained by the method known as pupillography comprising means for projecting the pairs of images consecutively, a slit for scanning the images produced by said projecting means, a photoelectric cell behind said slit adapted to receive the light passing through the latter, two stationary reflecting means, one for each of the two projected right and left images of the pupils, a rotatable reflecting means intermediate said two stationary reflecting means so arranged as to reflect the images coming from

the said stationary reflecting means across said scanning means when rotated, means for rotating said rotatable reflecting means at a uniform speed so that the said right and left images are moved across said slit consecutively at a uniform speed, means for amplifying the voltage developed by the light from said slit which falls on said photoelectric cell, means for applying a predetermined counter voltage to each of the amplified voltages obtained from the images of the pupil of the left eye, separate means for applying a different predetermined counter voltage to each of the amplified voltages obtained from the right eye, a single sweep oscilloscope adapted to be triggered by a small positive voltage, a rectifier for rectifying the voltages resulting from the combination of amplified voltages and counter-voltages the output of which is connected to the direct input terminal of said oscilloscope, means for resetting the oscilloscope after each image has been scanned, and means for photographing a corresponding portion of each response curve that is traced on the oscilloscope to graphically register the measured dimensions of the pupils.
